UNITED STATES PATENT OFFICE.

JACOB O. HARVIE, OF CHEYENNE WELLS, COLORADO.

WELL-CASING MACHINERY.

1,197,287.

Specification of Letters Patent. Patented Sept. 5, 1916.

Application filed June 22, 1916. Serial No. 105,203.

To all whom it may concern:

Be it known that I, JACOB O. HARVIE, a citizen of the United States of America, residing at Cheyenne Wells, in the county 5 of Cheyenne and State of Colorado, have invented certain new and useful Improvements in Well-Casing Machinery, of which the following is a specification.

This invention relates to devices for perforating and cleansing the interiors of well-casings and its object is to provide a simple and inexpensive structure which will not only remove projections and excrescences from the interior surfaces of well-casings, 10 but will cut a plurality of slits in the well-casing adjacent the bottom thereof. It is therefore possible to restore the flow of water to a well-casing which has become clogged by rust, sand or the like.

15 Further objects and advantages of the invention will be set forth in the detailed description which now follows.

In the accompanying drawing, Figure 1 is a side elevation of one form of the perforator; Fig. 2 is a like view of a modified form thereof; and Fig. 3 is a perspective view of one of the rasps used for removing 20 projections from the interior of the casing.

Like numerals designate corresponding 25 parts in all of the figures of the drawing.

Referring to the drawing and particularly to Fig. 1, 5 designates a rod having bolts 30 and 7 passing laterally therethrough. Bowed saw-blades 8 and 9 have their upper 35 and lower ends supported by the bolts 6 and 7 respectively. Springs 10 and 11 surround said bolts and normally tend to thrust the saw-blades outwardly. It will be noted that the teeth 12 of the saw-blades 40 are disposed outwardly for a purpose hereinafter set forth.

In the form of the device illustrated in Fig. 2, saw-blades like those shown in Fig. 1 are employed but in this case the supporting member 5^a is a tube instead of a rod and the springs 10^a, 11^a are disposed upon 45 bolts 6^a, 7^a inside of the tube 5^a and bear directly between the ends 8^a, 9^a of saws 8^a and 9^a. These saws are movable toward and 50 from each other through slots 5^b formed in the wall of the tube 5^a. Instead of the saws 8 and 9 or 8^a and 9^a I may employ bowed rasps such as are illustrated in Fig. 3. These rasps serve to remove any projections 55 or excrescences which may exist upon the

inner surface of the well-casing, while the saw-blades serve to cut slits through the well-casing adjacent the lower end thereof to reestablish any flow of water which may have been cut off by the accumulation of 60 rust, sand, mud or the like.

It is to be noted that the supporting members 5 and 5^a are adapted for use with either the saw-blades or the rasps.

While the elements shown and described 65 are well adapted to serve the purposes for which they are intended, it is to be understood that the invention is not limited to the precise construction set forth, but includes within its purview such changes as 70 fairly come within the spirit of the appended claims.

Having described my invention, what I claim is:

1. A device of the character described, 75 comprising a support and a bowed, yieldingly mounted cutting member carried thereby.

2. A device of the character described, comprising a support and a plurality of 80 bowed, yieldingly mounted cutting members carried thereby and projecting radially therefrom.

3. A device of the character described, comprising a support and a plurality of 85 yieldingly mounted bowed members carried thereby having saw-teeth upon their convex faces.

4. A device of the character described, comprising a support having bolts passing 90 laterally therethrough, bowed saws mounted for movement toward and from each other upon said bolts and springs normally tending to force said saws outwardly.

5. A device of the character described, 95 comprising a tubular support having slots in its walls, bowed saw-blades having their ends disposed inside of said tubular support and their convex faces disposed outwardly thereof, and springs within the tubular support and bearing between the ends 100 of said saws and normally tending to force them apart.

In testimony whereof I affix my signature in the presence of two witnesses.

JACOB O. HARVIE.
